UNITED STATES PATENT OFFICE.

HARRY T. KINGSBURY, OF KEENE, NEW HAMPSHIRE.

SPRING-MOTOR.

No. 824,248.

Specification of Letters Patent.

Patented June 26, 1906.

Application filed March 18, 1904. Serial No. 198,814.

To all whom it may concern:

Be it known that I, HARRY T. KINGSBURY, a citizen of the United States, residing at Keene, in the county of Cheshire, State of New Hampshire, have invented certain new and useful Improvements in Spring-Motors, of which the following is a description, reference being had to the accompanying drawings and to the letters of reference marked thereon.

My invention relates to spring-motors particularly adapted to mechanical toys.

The object of the invention is to provide a simple and inexpensive motor in which the spring may be quickly rewound from the driving-axle. This object I accomplish by the construction shown in the accompanying drawings, in which—

Figure 1 is a side elevation of my improved motor. Fig. 2 is a plan thereof. Fig. 3 is a plan of a modified form. Fig. 4 is a sectional side elevation of the right side of Fig. 3. Fig. 5 is a perspective of a further modification, and Fig. 6 is a plan of a further modification.

In Figs. 1 and 2, A represents the driving-axle, carrying the ground-wheels A' A' and mounted to rotate in bearings A², depending from the frame or part A³. The axle A is provided with a collar a' and a fixed pinion b, spaced apart to receive a large gear-wheel a between, the gear a being loose on the axle and provided with a pawl c, engaging the pinion b. The pawl c locks the gear a to the axle when the latter is rotated rearwardly in the operation of winding the spring B. The gear a meshes into a small pinion d, loose on a short axle d', mounted at one end in the frame A³ and at its other end in an angle-bracket A⁴, depending from the frame A³. The pinion d meshes with a crown-gear e on the end of the longitudinal drum B', about which the helical spring B is coiled. One end of the drum is journaled in the bracket A⁴, and the other end is journaled in a bracket A⁵. One end of the spring B is secured to the crown-wheel e or to the drum B', while the other end is secured to the bracket A⁵. It follows, therefore, that when the axle A is rotated rearwardly by moving the ground-wheels quickly to the rear the pinion b will rotate the loose gear a rearwardly through the medium of the pawl c and the gear a will in turn rotate a pinion d, which in turn will rotate the crown-

wheel c, and the latter will wind the spring B upon the drum.

The winding mechanism having been described, I will now describe the transmission or driving mechanism. At one end of the pinion d is a large loose gear h, provided with a pawl f, which engages the pinion d in such manner that when the pinion is being rotated by gear a to wind the spring the pawl will not lock the pinion d to gear h; but when the winding has been completed and the motor released the rearward rotation of the pinion d will engage the pawl f and carry it and the large gear h around to the rear, and as the large gear h meshes into the pinion b, fast on axle A, the latter will be rotated in a forward direction, and so propel the toy to which the motor may be applied. In such forward rotation of the axle the pinion b is free to rotate without being locked by pawl c to the large winding-pinion a. The large gear a is thus idle in the unwinding of the motor-spring, and the large gear h is active, while in the winding of the spring the large winding-gear a is active and the large transmitting-gear h is inactive.

In Figs. 3 and 4 the drum B' is journaled parallel with the axle A instead of at right angles thereto, as in Figs. 1 and 2, and both are journaled in bearings A⁹. In these figures a² is the large winding-gear loose on the axle A, b² is a ratchet-wheel fast on the axle, and c² is the pawl adapted to lock the gear-wheel a² to the axle when the latter is rotated rearwardly, but allow the axle free forward rotation. The gear-wheel a² meshes with an idle pinion e', which in turn meshes with a pinion d², loose on the axis of the drum B' and having connected with it a flange d³, to which one end of the spring B is secured. Reverse movement of the winding-pinion d² is prevented by a pawl f², pivoted to the frame. The opposite end of the drum is provided with a fixed transmitting-gear h², to which the opposite end of spring B is secured, and this gear h² meshes with a small gear g, fast on the axle. Thus after the spring has been wound by a quick rearward movement of the toy along the floor and the toy released the winding-gears will remain idle and the spring will rotate gear h² rearwardly and it in turn will rotate pinion g and axle A forwardly.

In Fig. 5 the spring-motor is wound by the forward movement of the axle and ground-

wheels. In this form of the invention the axle A is provided with a large loose winding-gear a^4 , having its hub provided with a groove a^5 to receive the end of a shifting-lever a^6 . The inner face of the gear a^4 is provided with two clutch-studs p , while the axle is provided with fixed clutch-arms a^7 a^7' , adapted to be engaged by the studs p when the gear a^4 is moved inwardly along the axle. 5 The gear a^4 meshes with a pinion d^4 , loose on the axis of the drum B' and having a flange d^5 , to which one end of the spring B is secured. Reverse motion of pinion d^4 is prevented by a pawl f^4 , pivoted to the frame. 10 The opposite end of the spring is secured to a large gear h^4 , secured to that end of the drum and meshing with a small pinion g^4 , fast on the axle. Thus when the axle is clutched to the large gear a^4 and rotated forwardly the 15 spring will be wound, and then by unclutching the axle and gear a^4 the gear h^4 will rotate rearwardly, and so impart forward rotation to the axle. 20

In Fig. 6 a further modification is shown, 25 and the drum or core B², about which the spring B is wound, is bent upon itself. This bending of the drum may take any form that will allow of the winding and unwinding of the spring. The purpose of the bending or 30 curving of the drum or core is to allow of a greater length of spring in a given space than would be possible with a "straight" drum or core. This is particularly advantageous in toys where there is only space sufficient for a 35 short length of drum, and by bending the drum or core upon itself, as in Fig. 6, twice the length of spring may be employed, and so the vehicle will be propelled twice the distance.

40 The core or drum B² is supported in any suitable manner from the vehicle-body, and the spring is secured at one end to the drum or core and at its other end connected to a flanged pinion d^6 , loose on the laterally-bent 45 end B³ of the core or drum. The axle A is provided with a large loose gear-wheel a^{12} , having a pawl c^{12} to lock it to a small fixed pinion b^{12} , said large gear meshing with the flanged pinion d^6 , so that when the axle A is 50 rotated rearwardly the pinion b^{12} will carry large gear a^{12} rearwardly, and this in turn will rotate pinion d^6 forwardly, and so wind the spring. Reverse action of the spring will rotate pinion d^6 , which will in turn rotate 55 a large transmission-pinion h^{12} by means of a pawl f^{12} , and the large pinion h^{12} meshes with the small pinion b^{12} , and so rotates the axle forwardly.

I do not restrict myself to the particular 60 mechanism shown, as the same may be modified without departing from the scope of my invention. It will be seen that in the several forms of the invention the rewinding of the motor is far more quickly effected than 65 would be the case where the winding is effect-

ed by merely reversing the motion of axle and the usual train of propelling-gears, as the latter operation is necessarily very slow.

Having thus described my invention, what I claim as new, and desire to secure by Letters 70 Patent, is—

1. In a wheeled, keyless toy, the combination with the axle and ground-wheels, of a quick-winding motor, comprising a spring, permanently-meshed gearing connecting 75 said axle and spring and including a large loose gear on the axle, a clutch mechanism connecting the said large loose gear to the axle for rotation therewith in one direction to wind the spring, a large transmission-gear 80 operatively connected with and driven from the spring in its unwinding movement, and a small gear on the axle in permanent mesh with said large transmission-gear; substantially as described. 85

2. In a wheeled, keyless toy, the combination with the axle and ground-wheels, of a quick-winding motor, comprising a spring, permanently-meshed gearing connecting said axle and spring and including a large 90 loose gear on the axle, a one-way clutch mechanism connecting said large gear to the axle for rotation therewith in one direction to wind the spring, a large transmission-gear operatively connected with and driven from 95 the said spring in its unwinding movement, and a small gear on the said axle in permanent mesh with said large transmission-gear; substantially as set forth.

3. In a wheeled, keyless toy, the combination 100 with the axle and ground-wheels, of a quick-winding motor comprising a spring, a gear connected to one end of said spring, a short shaft having a fixed pinion meshing with said gear, a large winding-gear loose on 105 the axle and meshing permanently with said fixed gear, a one-way clutch device connecting said winding-gear and axle, a large transmission-gear loose on said short shaft, a one-way clutch device connecting said transmission-gear with said short shaft, and a fixed 110 pinion on the axle and in permanent mesh with said transmission-gear; substantially as set forth. 115

4. The combination in a keyless, wheeled 120 toy, with the vehicle-axle and the ground-wheels, of a motor comprising a spring, a gear-wheel connected therewith, a large loose winding-gear on the axle, a small fixed pinion also on the axle, a pawl on the large gear and engaging said pinion, a small intermediate pinion in permanent mesh with the first-named gear-wheel and also in permanent mesh with the said large winding-gear, and a large loose transmitting-gear in permanent 125 mesh with the fixed pinion on the axle and having a pawl engaging the said intermediate gear-wheel, substantially as set forth.

5. The combination with the axle and its 130 ground-wheels, of a motor comprising a

drum at an angle to the axle, a crown-wheel on the end of the drum, a helical spring on the drum and connected at one end to a fixed part and at its other end connected with the drum, a large loose winding-gear on the axle, a pawl-and-ratchet mechanism connecting the two, a fixed pinion on said axle, a small intermediate pinion connecting the said large winding-gear and the crown-wheel, and a large loose transmitting-gear engaging the 10 pinion on the axle and having a pawl engaging the said intermediate pinion.

In testimony whereof I affix my signature in presence of two witnesses.
